UNITED STATES PATENT OFFICE.

WILLIAM D. PIERSON AND FRED S. VAN VALKENBURG, OF WATERBURY, CONNECTICUT, ASSIGNORS TO THE WATERBURY FARREL FOUNDRY AND MACHINE COMPANY, OF WATERBURY, CONNECTICUT, A CORPORATION OF CONNECTICUT

PRESS.

Application filed February 13, 1928. Serial No. 254,030.

This invention relates to a new and improved press, referring more particularly to a multiple plunger press for cutting a blank from a strip of metal and performing a sequence of operations thereon to produce a finished article.

The invention is not limited to this particular type of machine but is peculiarly adapted thereto, and for the purpose of illustrating the invention we have chosen such form of mechanism.

It is one of the objects of this invention to provide means whereby the tools that operate upon plural rows of presented blanks may be so held in series as to permit of two adjustments, that is, one series in a path at substantially a right angle to the other series and as a unit, and each tool in a path substantially parallel to its axis, such adjustments to be obtained with the minimum labor, skill and expenditure of time, and with a certainty that the parallel arrangement of the tools will be maintained.

Further objects and features of the invention will be apparent from the accompanying drawings in connection with the description hereinafter contained.

To these, and other ends, our invention consists in the press, having certain details of construction and combinations of parts as will be hereinafter described and more particularly pointed out in the claims.

Referring to the drawings, in which like numerals of reference designate like parts in the several figures;

Figure 1 is an elevation of a press gate and adjacent parts embodying our improved mechanism;

Figure 2 is a plan view of the tool holder and tools;

Figure 3 is an enlarged sectional view of the gate and associated mechanisms, taken generally upon line 3—3 of Figure 1;

Figure 4 is a fragmentary plan view of a portion of the gate;

Figure 5 is a plan view of one of the strip-
per plates;

Figure 6 is a plan view of the body member with some of the parts associated therewith, the parts in section being taken generally upon line 6—6 of Figure 1; and

Figure 7 is a fragmentary elevation of our improved press, the parts in section be-

ing taken generally upon line 7—7 of Figure 1.

55

This machine is of the type having a gate carrying a plurality of punches movable toward and away from a bed, to which are secured a plurality of dies, and through which gate a blanking slide is independently operated.

60

In the embodiment of the invention as herein shown and disclosed: 10 designates the body of the press or the like, 11 the guide rods connected therewith, and 12 the gate which is guided by the rods and movable toward and away from the bed by means (not shown) but common in the art.

65

Movably mounted in this gate is a blanking slide 49 upon which a punch holder 88 carrying a blanking punch 50 is adjustably secured.

70

The timing of the movement of the gate 12 and blanking slide 49 is such that when the former is in substantially its extreme down position, the latter is in substantially its extreme up position and vice versa for a purpose hereinafter disclosed.

75

The gate is provided with lips 13 and a plurality of slots 14, the latter being arranged in series upon opposite sides of the center of the gate. While in the form herein shown the gate is movably mounted upon the rods 11, obviously it may be mounted in ways or the like, as is common in presses.

80

The companion punch frames 15 are preferably U-shape in cross section and provided with recesses 16 in one face, into which project the lips 13 upon the gate 12, and thus assure a correct alignment with the gate, irrespective of the relative position of the punch frames one with the other.

85

The frames are adjustably secured to the gate by screws 17, each of which passes through a slot 14. By loosening these screws, the frames may be moved toward and away from each other in guided alignment with each other.

90

Adjustably secured in each of these frames 15 are a plurality of punch holders 18, having shanks 19, 20 and 21 thereon, preferably of different diameters. The shank 21 of the holder passes through an opening in the arm 22 forming part of the frame 15 and by means of suitable nuts 23 and 24 are adjustably held against endwise movement rela-

100

105

tively to the frame 15. Caps 25 secured to the arm 26 forming part of the frame 15 secure the punch holders adjacent to the tool end thereof.

5 Fixed in the lower end of each of the punch holders 18 is a punch carrier 27, in which is the punch 28. The form or shape of the punch holders 18 and the means of securing the punch 28 thereto may be varied 10 within a wide range without departing from the spirit of our invention.

Each punch holder has an axial adjustment within the frame 15 and all the punch holders in each series move as a unit in correct alignment with each other toward and away from the punch holders in the adjacent series, through movement of the frames 15 by manipulation of the screws 17.

20 The die and die holding mechanism, as shown herein, comprise companion die beds 39, each of which is secured to the body 10 by screws 44, or the like, that pass through slots 79 in the body, to permit adjustment of the die beds toward and away from each other. Within each die bed is a die block 40 that is secured by screws 45 or the like, and a plurality of dies 42 are held therein by nuts 43.

30 Movable in the die bed 39, above the die blocks is the transfer slide 41, having a receiving die 80 fixed therein by the screws 81 or the like, and hinged therein the fingers 78, which are arranged in pairs and moved inwardly by the springs 82 or the like.

35 Fixed to the body 10 is the bracket 51, within which is the slide 52. A reciprocatory movement is given this slide from a cam 53 on a rotating shaft 54 and engaging rolls 55 journaled on the slide opposite each other. Secured to the slide 52 is a transmission plate 56 having stop lugs 57 thereon. A link 58 for each transfer slide is adjustably secured to the transmission plate by a screw 59 which passes through a slot in the link. 40 Endwise adjustment of the link is obtained through a screw 60, which has a threaded engagement with a lug 57, a link 58 at one end having a right hand thread and the other a left hand thread. Nuts 61 upon the screws 60 provide means for locking the screws against movement in its adjusted positions. At the outer end of each link 58 is a stud 62 that is threaded into a slide block 63 which projects into a longitudinal recess 64 in the transfer slide 41. The reciprocating movement of the slide 52 is imparted to the transfer slides 41 through the plate 56 and links 58. The position of each of the transfer slides 41 relative to the slide 52 may be varied by changing the relative positions of the links 58. Movement of the transfer slides 41 toward and away from each other is accommodated through the longitudinal recesses 64, which through the studs 62 and slide blocks 63 insure a positive connection

between the transfer slides and the slide 52 irrespective of the relative position of the transfer slide.

The metal strip 65, from which the blanks are cut, is fed under the blanking punch 50 at an angle to the direction of movement of the transfer slides 41, substantially as shown in Figure 6. This strip is fed from a spool 66 journaled on a shaft 67 supported in a block 68 adjustably secured by the bolt 69 to a bracket 70. Endwise movement of this strip is obtained by passing the same through a pair of feed rolls 71 journaled in a bracket 72 on the body 10, the rolls being geared together by gears 73 and actuated from a rotating shaft 74 through an intermediate flexible connection 75 of any well known type. Bolts 91 that pass through openings 92 in the bracket 72 permit the latter to be secured in various positions. The strip in its movement through the press travels over the die plate 83, containing the cutting dies 84.

25 A limited vertical adjustment for the punches 50 is obtained through manipulation of the wedges 89 which pass through suitable openings in the punch holder 88. The relative positions of the punch holder 88 toward and away from each other is varied by placing suitable filling pieces 90 of varying thicknesses between the slide 49 and punch 95 holder 88.

35 In operation the two blanking slides descend and each blanking punch 50 in conjunction with a cutting die 84 cuts a blank 85 from the strip, which is pushed into a receiving die 80 connected with the transfer slide 41 against the bottom plate 86 in the die bed.

40 The stripper plate 76, having openings 77 therein to receive the punches 50, prevents the strip 65 from being pulled upwardly with the punches as they ascend. After the blanking punch is withdrawn the transfer slide moves to the left, as shown in Figures 1 and 6, carrying the blank 85 to the first drawing punch 28 in the series, which forms the blank into a shell 46 as it passes down through the die 42. During this drawing operation the transfer slide is returned to its former position and as the gate ascends carrying the punches 28, the blanking slide 49 descends and the punches 50 cut two new blanks.

45 As each punch 28 is withdrawn from a die 42, the lifter punch 47, operated in a well known manner, moves the shell 46 upwardly between a pair of yielding fingers 78. During the next movement of the transfer slide to the left, these fingers carry the shell 46 to a point below the next punch 28 in the series, where it is subjected to another operation and so on until the shell has been subjected to sufficient operations to form a completed article which is discharged through an opening 87 into a receptacle conveniently arranged to receive it.

We have provided mechanism for stripping the work from the punches 28 that is adapted to perform its function without adjustment irrespective of the relative position of the punches toward and away from each other.

This stripper mechanism comprises a plate 37 held by posts 38 in a fixed position relatively to the body 10 or the like, and through which is threaded a plurality of sleeves 29 locked against movement in their adjusted positions by the nuts 30. Movable in these sleeves 29, by means of the springs 48, are the studs 31, having connected therewith the stripper plates 32, held against rotation thereon by the dowel pins 33, or the like. The other end of each of these stripper plates 32 projects into a recess 35 in a stripper sleeve 36, which encircles the punch 28, a slot 34 being provided for this purpose. The slot 34 is of sufficient depth to permit the engagement of the plates 32 with the sleeve 36 in its innermost position and equally so in its outermost position, and thus the stripper mechanism in any of the varying positions of the punches will operate without adjustment of any of its parts.

As shown, the blanks as cut from the strip are several spaces apart but at each feed of the strip new blanks are cut therefrom as close as practicable to the openings left by the blanks last cut, thereby avoiding waste. By keeping the same relative spacing a variation in the size of the blanks is permissible by changing the angle of travel of the strip 65 as it passes under the blanking punches. Such varying paths of travel being accommodated by the adjustability of the bracket 72 on the body 10 and the block 68 on the bracket 70. This adjustment to produce blanks of various sizes results in a consequent variation in the size of the shells produced from the blank, which in turn is provided for by adjustment within reasonable limits by the die beds and punches 50 and 28 toward and away from each other.

What we claim as new and desire to secure by Letters Patent, is:—

1. In mechanism of the character described; a movable member; a plurality of blocks having an intermeshing engagement therewith; a plurality of punch holders connected with each of said blocks; means for adjustably securing each of said blocks to said member; and means for adjusting each of the punch holders relatively to the block in a path at substantially a right angle to its path of adjustment upon the member.

2. In mechanism of the character described; a plurality of series of punch holders; and means for mounting each of said series of punch holders upon a member, whereby they may be adjustable relatively to the member and maintained in their alignment one with the other; a punch within each

of said punch holders; and a stripper for 65 each of said punches which will maintain its operative relation with the punch mechanism without adjustment irrespective of the relative position of the punch holder.

3. In mechanism of the character described; a gate; a plurality of punch frames associated therewith and movable in substantially parallel lines toward and away from each other; means for adjustably securing each of the frames to the gate; a plurality of punch holders connected with each of the frames and adjustable relatively thereto, the arrangement of said frames and gate being such that all of the punches associated with one of the frames are adjusted therewith as a 80 unit relative to the punches in the other frame.

4. In mechanism of the character described; a gate; a plurality of substantially U-shaped punch frames associated therewith and movable in substantially parallel lines toward and away from each other; means for adjustably securing each of the frames to the gate; a plurality of punch holders connected with each of the frames and adjustable relatively thereto, the arrangement of said frames and gate being such that all of the punches associated with one of the frames are adjusted therewith as a unit relative to the punches in the other frame, a portion of the 95 means for adjustably connecting the punch holders to the frame being within the open space between the substantially parallel walls of the frame.

5. In mechanism of the character described; a recessed gate; a plurality of punch frames associated therewith and movable in substantially parallel lines toward and away from each other; means for adjustably securing each of the frames to the gate; a plurality of punch holders connected with each of the frames and adjustable relatively thereto, a portion of the adjusting and securing means being within a recess in the gate, the arrangement of said frames and gate being such that 110 all of the punches associated with one of the frames are adjusted therewith as a unit relative to the punches in the other frame.

6. In mechanism of the character described; a gate; a plurality of substantially U-shaped punch frames associated therewith and movable in substantially parallel lines toward and away from each other; means for adjustably securing each of the frames to the gate; punch holders, each of which has a 115 shank portion that projects through an opening in one of the substantially parallel arms of the frames; threaded securing means on the punch holder, a portion of the securing means being upon one side of one of said parallel arms and another portion upon the opposite side, the arrangement of said frames and gate being such that all of the punches associated 120

with one of the frames are adjusted therewith as a unit relative to the punches in the other frame.

7. In mechanism of the character described; 5 a gate; a plurality of punch frames associated therewith and movable in substantially parallel lines toward and away from each other; means for adjustably securing each of the frames to the gate; punch holders, each of 10 which has a shank portion that projects through an opening in one of the substantially parallel arms of the frames; threaded securing means on the punch holder, a portion of the securing means being upon one side of 15 one of said parallel arms and another portion upon the opposite side; a cap for securing each punch holder to the other of said parallel arms, the arrangement of said frames and gate being such that all of the punches associated 20 with one of the frames are adjusted therewith as a unit relative to the punches in the other frame.

8. In mechanism of the character described; a gate; a plurality of substantially 25 U-shaped punch frames associated therewith and movable in substantially parallel lines toward and away from each other; means for adjustably securing each of the frames to the gate; punch holders, each of which has a 30 shank portion that projects through an opening in one of the substantially parallel arms of the frame and angular in cross section within the other of said parallel arms; threaded securing means on the punch holder, a portion 35 of the securing means being upon one side of one of said parallel arms and another portion upon the opposite side, the arrangement of said frames and gate being such that all of the punches associated with one of the 40 frames are adjusted therewith as a unit relative to the punches in the other frame.

9. In mechanism of the character described; a plurality of series of punch holders; and means for mounting each of said series of 45 punch holders upon a member, whereby they may be adjustable relatively to the member and maintained in their alignment one with the other; a punch within each of said punch holders; a fixed part; a sleeve in the fixed part 50 for each of the punch holders; a plunger

within each of the sleeves; a stripper plate associated with each of the plungers and having an operative connection with an adjacent punch.

10. In mechanism of the character described; 55 a plurality of series of punch holders; and means for mounting each of said series of punch holders upon a member, whereby they may be adjustable relatively to the member and maintained in their alignment one with the other; a punch within each of said punch holders; a fixed part; a sleeve in the fixed part for each of the punch holders; a plunger within each of the sleeves; a stripper plate associated with each 60 of the plungers and having an operative connection with an adjacent punch; and yielding means for moving the plunger in one direction.

11. In mechanism of the character described; 65 a plurality of series of punch holders; and means for mounting each of said series of punch holders upon a member, whereby they may be adjusted relatively to the member and maintained in their alignment one 70 with the other; a punch within each of said punch holders; a fixed part; a sleeve in the fixed part for each of the punch holders; a plunger within each of the sleeves; a sleeve associated with each punch; a stripper plate 75 associated with each of the plungers and having an operative connection with an adjacent sleeve.

12. In mechanism of the character described; 80 a movable member; a punch holder associated therewith, whereby the same may be adjusted relatively thereto; a punch holder; a punch connected with the punch holder; a stripper thereon; and independent means for in part controlling the action of the stripper, comprising a plunger movably mounted in the fixed part; and a connection between the stripper and plunger, the latter having a movable engagement with the stripper to accommodate various relative positions of the 85 punch.

In testimony whereof we have hereunto affixed our signatures.

WILLIAM D. PIERSON.

FRED S. VAN VALKENBURG.
